UNITED STATES PATENT OFFICE

GILES BOLIVAR ROE, OF PAYNE'S POINT, ILLINOIS.

IMPROVEMENT IN STEAM WATER-ELEVATORS.

Specification forming part of Letters Patent No. 122,332, dated January 2, 1872; antedated December 29, 1871.

SPECIFICATION.

I, GILES BOLIVAR ROE, of Payne's Point, in the county of Ogle, State of Illinois, have invented certain Improvements in Steam Water-Elevators, of which the following is a specification:

Description of the Accompanying Drawing.

Figure 1 is a section of a machine embodying my invention. Fig. 2 is a section of the valve.

General Description.

A represents the well or reservoir. B is the general discharge-pipe. c and c' are the air-chambers. D is the pipe-valve. e and e' are the steam and water-throats in the valve D. f and f' are the lever-arms for adjusting the valve D. E¹ is the steam-pipe that connects the cylinders G and G' to the steam-boiler by a flexible hose-pipe. E² is the left escape-pipe for the waste steam to escape while the cylinder G is filling with water. E³ is the right escape-pipe for the waste steam to escape while the cylinder G' is filling with water. G and G' are the metallic cylinders, joined and connected and submerged, as shown in Fig. 1. h and h' are the loaded buoys attached to the lever-arms f and f'. i and i' are the lower heads in the cylinders G and G'. K and K' are the foot-valves in the lower end of the cylinders G and G'. l and l' are sections of the discharge-pipe, each having a check-valve to prevent the water from flowing back into the cylinders G and G'. m and m' are the foundations upon which the superstructure sits. All the above, as shown in Figs. 1 and 2, constitutes the steam water-elevator.

The Mode of Operating the Water-Elevator.

The connections being made, as shown in Fig. 1, the steam is turned on and passes down through the steam-pipe E¹ and the throat e' into the metallic cylinder G', and forces the water up through the extension-pipe l' and B to the point of delivery. When the water is

driven from the cylinder G' the float h' is relieved of the buoyant effect, and the weight in the buoy h' depresses the lever f', which moves the valve in such a manner that the throat e connects with the steam-pipe E¹, and the steam passes through the throat e into the cylinder G, and forces the water up through the extension pipes l and B to the point of delivery. As the throat e is placed in connection with the steam-pipe E¹ the throat e' is placed in connection with the escape-pipe E³. As the water is being forced from the cylinder G the waste steam escapes from the cylinder G' through the throat e' while in connection with the escape-pipe E³. While the steam is so escaping the buoyant effort of the water forces open the valve K' and fills the cylinder G' with water. The water being all forced from the cylinder G, the buoy h is relieved of the buoyant effort of the water. The weight in the buoy h depresses the lever f, which moves the valve in such a manner that the throat e' connects with the steam-pipe E¹. The steam passes into the cylinder G' and forces the water therefrom at the same time the cylinder G is being filled with water, and the waste steam is escaping through the throat e and the discharge-pipe E².

Thus it will be seen that this water-elevator is automatic in its operating, and that one continual stream of water may be thrown therefrom as long as the steam is connected therewith.

Claim.

The valve D with its throats e and e', and its lever-arms f and f', and its loaded buoys h and h', and the discharge E² and E³, in combination with the cylinders G and G', substantially as and for the purpose hereinbefore set forth.

GILES BOLIVAR ROE.
